CLAIM

The ornamental design for a vented dental pin, as shown and described.

DESCRIPTION

FIG. 1 is a top plan view of a vented dental pin, showing my new design;

FIG. 2 is a front elevational view thereof, the rear being substantially similar in appearance;

FIG. 3 is a side elevational view thereof, the opposite side being substantially similar in appearance; and

FIG. 4 is a bottom plan view thereof; and

FIG. 5 is a sectional view taken along line 5—5 of FIG. 2.

FIG. 1

FIG. 2

FIG. 3

FIG. 4

FIG. 5
